WINDOW STAY

Adolph Ronning, Minneapolis, Minn.

Application June 9, 1938, Serial No. 212,734

9 Claims. (Cl. 292—276)

This invention relates to improvements in window hardware or window stays.

The type of hardware here in mind is that which is used as stay means for the fastening of storm windows and screens in window frames and, in order to facilitate the understanding of my invention, the more usual types of such devices will be briefly discussed. Probably the most popular arrangement of the storm windows and screens is to provide them with hooks at their upper ends which pivotally engage hangers affixed to the upper ends of the window frames so that the storm windows or screens may swing from their upper ends and may be readily interchanged by disengaging them from the hangers. However, in addition to the above structures it is necessary to provide some means to lock the lower ends of the storm windows or screens and to permit them to be swung outwardly and retained in a slightly opened position whenever desired, and it is with devices of this kind that I am concerned. Heretofore the storm windows and screens have been simply provided with hooks or latches for holding them closed and where necessary, with an assembly of swinging arms connected to the windows or screens and engaging brackets secured to the window frame. These arms are conventionally arranged to lock the storm windows or screens or to support them in an outwardly swung position at their lower ends. All of such devices, however, are relatively crude, difficult to operate, and make the operation of interchanging the storm windows and screens very difficult and one which is dreaded in almost every instance. Furthermore, the prior devices have all employed fastening and supporting assemblies which required the use of large projecting parts on the storm sash and screens, thus making it very difficult to store the unused windows or screens away compactly and often resulting in breaking or otherwise disarranging the parts.

Having in mind these facts, it is the primary object of my invention to provide means whereby a storm window or screen may be readily locked in place in a window frame or held in any adjusted angular position therein, and wherein the parts attached to the storm window or screen itself have a minimum projection, or none at all, to thereby facilitate storage of the windows and screens and prevent breakage of parts.

Another object is to provide window hardware for this purpose which may be readily attached to the storm windows, screens and window frames, and wherein the necessary disengage-

ment of the parts when interchanging the windows and screens may be readily carried out without the use of any tools and without danger of breaking any of the parts.

Another object is to provide window hardware of this kind which may be easily operated to swing the lower end of the storm window or screen outward from the window sill and which will then effectively support the parts in the selected or desired positions.

Another object is to provide hardware devices of this nature which may also be used to positively lock the storm window or screen in closed position and which is extremely simple and durable in construction and convenient in operation.

These and other more detailed and specific objects will be disclosed in the course of the following specification, reference being had to the accompanying drawings, in which—

Fig. 1 is a fragmentary perspective view showing a section of a window frame and storm window with my invention applied thereto, and with the storm window partially opened.

Fig. 2 is a fragmentary detail plan view showing the connection between the pull cable and arm and the storm window.

Fig. 3 is a similar view, showing a modified connection.

Fig. 4 is a side elevation of the assembly in closed position, the storm window being shown in section and with a further modification of the connection between the window and operating parts therefor.

Fig. 5 is a horizontal section along the line 5—5 in Fig. 4.

Fig. 6 is a fragmentary perspective view illustrating the lock for the storm window or screen.

Fig. 7 is a side elevation, partially in section, and in a reduced scale, showing a modified type of device for adjusting and supporting a storm window or screen.

Fig. 8 is an enlarged, diametrical section along the line 8—8 in Fig. 7.

Fig. 9 is an elevation on an enlarged scale and partially broken away and in section, showing the drum and flexible member employed in the structure of Fig. 7.

Fig. 10 is an enlarged cross section along the line 10—10 in Fig. 7, showing the connection between the storm window and the flexible adjusting member.

Fig. 11 is an inside elevation of the connecting member for connecting the said flexible adjusting member to the window.

Fig. 12 is a cross section along the line 12—12 in Fig. 9.

Fig. 13 is an enlarged perspective view of the structure of Fig. 7, but including a lock for holding the storm window or screen in closed position.

Fig. 14 is a view similar to Fig. 7, but showing the assembly in another position.

Fig. 15 is a plan view of the assembly of Fig. 14, showing a part of the window frame in cross section.

Referring now more particularly and by reference characters to the drawings, A designates a window frame, B the storm window or screen, and C the device constituting the subject matter of the present invention. It is understood that the term "window frame" is used to denote the window in which the storm windows or screens are to be mounted and, for convenience in this description the term "window" will refer to the storm window which, of course, takes in the form of a frame of suitable size to fit the window frame A and having glass panes set in place in usual manner. The use of the term "window" for the moving part of the assembly is further justified for the reason that my hardware or device may also be employed for the locking or adjustment of swinging windows of all kinds, as well as storm windows. The window B is adapted to hang at its upper end from the window frame A by the usual detachable hangers (not shown) and is arranged to close against a vertical stop strip D secured to the frame A. Only one side of the entire assembly is shown in the drawings and described herein, but it will, of course, be understood that the structures described are duplicated at the other side. The window B is furthermore adapted to be opened by pushing it outwardly at its lower end so that it stands outwardly at an angle relative to the window frame A, as shown in Fig. 1.

My hardware device or assembly C comprises a carrier, guide member, or elongated bracket 5 which is secured vertically to the inner face of the stop strip D by screws 6, and has marginal flanges 7 terminating in inwardly turned lips 8 which define a vertical slot 9 and inner guideway space 10 which opens at upper and lower ends. This device is mounted adjacent the inner edge of the strip D and away from the edge against which the window B closes, in order thus to afford some clearance when the window is closed, as indicated at 11. A slide or guide block 12 is mounted in the guideway 10 to slide nicely therein, and carries a threaded stud 13 which extends loosely through the slot 9 to carry an adjustable locking knob 14 which is screwed therein. Interposed between the knob 14 and the lips 8 of the bracket 5 is a support arm 15 pivotally mounted at one end on the stud 13 and extended therefrom. The free end of this arm 15 terminates in a laterally turned pin 16 which is adapted to pivotally engage a connecting unit or fastener 17 secured to the window A. This unit 17 has a base 18 secured by screws 19 to the window, and has an ear 20 apertured to pivotally receive said pin 16. The arm 15 is of such length and the unit 17 is so mounted with respect to the position of the bracket 5, that when the window A is in closed position, the lever will swing inwardly over the bracket with its upper end aligned with the upper end of the bracket, and its lower end located near the lower end of the bracket so that the knob and block assembly (14—12) maintains its engagement with the bracket.

5 A flexible pull cable 21 is anchored at one

end 22 to the block 12, and at its other end has a loop 23 formed to slip over the pin 16 alongside the connecting unit 17, and intermediate its ends the cable is trained over a small pulley 24 which is rotatably pinned to the upper end of the bracket 5 at 25.

In operation, the window B is normally closed, and to open it, the knob 14 is first loosened and the lower end of the window is pushed outwardly away from the frame A. This action exerts a pull on the cable 21 causing the cable to draw the block 12 upwardly in the bracket 5 so that the arm 15 gradually assumes an angular position (Fig. 1). When the window is opened to the desired amount, the knob 14 is turned tight to frictionally lock the lower end of the arm 15 (and the block 12) in position, and the arm now braces the window and maintains it in the selected position. To again close the window the knob 14 is loosened and pushed downwardly causing the arm and cable to pull the window back against the strip D. The function of the cable 21 is to provide the necessary pull on the parts when the angle at which the arm 15 stands is unfavorable for such action. This is particularly true in closing the window, in which case the cable pulls directly against the window even when the arm stands nearly vertical, as will be understood. The space 11 between the bracket 5 and the window B provides the necessary clearance for the parts. The action of opening and closing the window, of course, requires the manipulation of the devices at each side of the window, but this is readily carried out by simultaneously loosening and adjusting one knob 14 with each hand.

In lieu of the connecting unit 17 as described with a single ear 20, I may employ a unit of identical form (Fig. 3) except that it has two spaced ears 20—20a, and in this case the cable loop 23 may be slipped over the pin 16 of the arm 15 between these ears. In either case it is contemplated that the arm 15 will have sufficient flexibility to permit it to be "sprung" aside enough to permit the pin 16 to clear the unit 17. This action then permits the arm to be disconnected from the window B and connected to a screen (not shown and also having similar units 17) easily and quickly, and without the aid of any tools. It will also be noted that when the arm is disconnected the storm window or screen carries only the small connecting units 17 which form very little projection on these parts and are not of such nature that they are readily broken or disarranged. The storage of the windows or screens is thus greatly facilitated.

Figs. 4 and 5 illustrate a similar assembly, but one which is modified in the connecting means between the arm 15 and window B to the end that no projecting parts whatever are mounted on the window. The bracket 5 and associated parts are all identical with those heretofore described, but the extended end of the arm 15 has the pin 16a extended at each end from each side thereof. The loop 23 of the pull cable 21 is hooked over one end of this pin 16a and the connecting unit 17a here takes the form of a socket element 26 exteriorly threaded to screw into a recess 27 cut in the window B. One wall of this socket element has an opening 28 into which the end of the pin 16a may enter (Fig. 5), and into which it is yieldably pressed by a spring 29 secured to the base of the socket element by either a screw 30 or rivet 31. The arm 15 thus enters the socket element 26 at its outer end, as shown, and is pivotally connected thereto so that the

operation of opening and closing the window (or screen) is exactly as heretofore described. When interchanging the windows and screens the arms 15 are simply pressed to one side against the springs 29 to release them from the socket elements 26 (in both windows and screens) and it will be readily evident that this type of connecting unit forms no projection whatever from the windows or screens.

For positively locking the storm window or screen in closed position, I provide the assembly shown in Fig. 6. A locking lever 32 is pivoted medially on the stud 13, between the knob 14 and arm 15, and has an extended arcuate hook or finger 33 which may be engaged with a loop 34 secured at 35 into the window B (or screen). A handle 36 extends from the lever for moving the hook 33 into, and out of, engagement with the loop 34 and, of course, when the lock is engaged it will be impossible to open the storm window. The hook 33 is so shaped that, when moved to enter the loop 34, it also exerts a pulling force on the window to draw it to a tightly closed position. The arm 15 may have a boss 37 formed near its lower end to enter and engage a socket 38 pressed in an extended portion 39 of the lever 32, to releasably retain the lever in its locked position. The operation of the remainder of the device is exactly the same as previously described, and the positive lock is, of course, only used when it is desired to close and lock the window (or screen). These locks are used on either, or both, sides of the window.

In lieu of the combination of rigid and flexible elements (15-21) for moving and supporting the window, I may employ a single element having both of these characteristics as disclosed in Figs. 7 through 12. In these views A again designates the window frame, B the storm window (or screen), and C my device or assembly for adjusting the window. The extensible member of the assembly C is designated at 40 and takes the form of an elongated strip of spring material, such as steel, formed into a normally concavo-convex or arcuate cross sectional shape so that it may be readily wound into a coil but, when extended, will have the property of maintaining a straight condition and resisting endwise stresses. This strip member 40 is wound or coiled up in a container or carrier 41 which is secured to the inner side of the window frame A and includes a fixed cup-like base 42 secured by means of a screw 43 and punched out teeth 44 to the frame. This base has an extended guideway 45 through which the member or strip 40 may slide in a flattened condition to enter and leave the carrier, and this guideway directs the strip outwardly toward the window B. A parted, expansible brake drum 46 fits within the coil 40a of the strip 40 and normally contracts in order to free this coil so that the strip may be readily pulled out of, or pushed into, the carrier. A cover plate 47 fits over the base 42 and has a central, cup-shaped depression 48 having an inner, annular, and angularly extended edge 49 located within the drum 46. The drum has cam lugs 50 punched inwardly at circumferentially spaced points, and these lugs have angular cam faces 51 which engage the edge 49 of the cover plate 47 so that, by pushing this plate inwardly over the base 42 (guided by the telescoping margins 52) the edge 49 will cam against the lugs 50 to expand the drum 46 and tighten the coil 40a. The strip 40 will thus be locked against movement, but by releasing the cover plate 47, the

brake drum 46 may again contract to free the strip. For thus operating the cover plate 47, I provide a stud 53 which is rigidly extended from the screen 43 through an opening 54 in the cover, and which carries a threaded knob 55 on its outer end to engage the cover (when screwed tight) and press it inwardly into the drum, or to allow the cover to move outwardly when unscrewed.

For releasably connecting the end of the strip 40 to the window B I provide a connecting unit 56 including a base 57 adapted to be screwed to the window and having an aperture 58 with diametrically opposed and radially extended notches 59. The end of the strip 40 is notched as at 60 to form a T-shaped head 61 which may enter the notches 59. The base 57 is so located on the window B that these notches lie at right angles to the normal position of the strip 40 and the strip must, therefore, be twisted on its axis a quarter turn in order to introduce the head 61 through the notches. When released the strip will then return to normal position, and the head will be locked within the base 57 as will be clearly evident. The operation of connecting and disconnecting the strip with respect to the window B (or the screen which, of course, also carries the units 56) is thus readily performed without tools. The base 57 may have its central portion formed out into a boss 62 in order to give 30 clearance space for the head 61 or the base may be fixed flatly to the window and a recess formed in the window beneath the base to give this clearance.

In operation, the knob 55 is normally screwed 35 tight to prevent movement of the strip 40 and the window is then held in adjusted position. However, by loosening this knob the strip is freed and the window B may be moved outwardly or inwardly to any desired position. Then by tightening the knob again the strip will be locked, and will support the window in the adjusted position, as will be understood. The window is, of course, provided with one strip 40 and carrier assembly 41 at each side. To change the window B for a 45 screen the strips 40 are simply twisted slightly to free them from the connecting units 56, and are then replaced in the units on the screen. The margins 52 of the base member 42 and cover 47 are provided with a rib 63 and groove 64 to prevent rotation of the cover as the coil 40a moves in the adjustment of the strip 40.

Fig. 13 discloses an assembly identical to that just described, but with means for positively locking the window or screen in closed position. The strip 40 is arranged in the carrier assembly 41 mounted on the frame A, and the strip is connected by the unit 56 to the storm window B for adjusting and supporting the same in any selected position. The lock comprises a lever 32a quite similar to that shown in Fig. 6, but this lever is shown as mounted in inverted position so that its hook or finger 33a moves downwardly to engage the loop 34a secured to the window. The lever 32a is pivotally mounted on the stud 53, or rather upon a reduced neck 65 on the knob 55 and may be manipulated by the handle 36a to engage or disengage the loop 34a and, of course, lock or unlock the window. A collar 66 fitted over the neck 65 prevents lateral displacement of the lever 32a and the lever may be secured in adjusted position by turning the knob up tight to clamp the lever.

The carrier assembly 41 may be mounted horizontally on the window frame A instead of ver-

tically, as heretofore shown, and this horizontal position is disclosed in Figs. 14 and 15. The operation is identically the same, and the window B is held in adjusted position by the strip 40, but, since the strip cannot bend edgewise, as the window opens and closes, the carrier 41 is pivotally mounted by a pin 67 to a bracket 68 secured to the frame A. The entire carrier assembly may thus rock freely in a horizontal plane as the angle of the strip 40 varies in the opening and closing of the window or screen.

From the foregoing it will be apparent that I have provided extremely simple and effective means for adjusting and locking storm windows and screens with respect to a window frame, and which permits the convenient changing of windows and screens without tools.

It is understood that suitable modifications may be made in the structure as disclosed, provided such modifications come within the spirit and scope of the appended claims.

Having now therefore fully illustrated and described my invention, what I claim to be new and desire to protect by Letters Patent is:

25. 1. A device for adjusting a swinging closure member mounted in a window frame, the same comprising a bracket secured to the frame and having an elongated slot, an arm adjustably connected at one end to the slot and bracket and movable therein for varying its extension from the frame, the opposite end of the arm being releasably connected with the closure member, a flexible cable connected to opposite ends of the arm, and a pulley supporting the cable between its ends.

30. 2. A device for adjusting a swinging closure member mounted in a window frame, the same comprising a bracket secured to the frame and having an elongated slot, an arm adjustably connected at one end to the slot and bracket and movable therein for varying its extension from the frame, the opposite end of the arm being releasably connected with the closure member, a flexible cable connected to opposite ends of the arm, and a pulley supporting the cable between its ends and at a point in alignment with the slot in which the arm is moved.

35. 3. A device for adjusting and locking a closure, the same comprising a carrier assembly and a supporting member extensible therefrom for engagement with the closure, means on the carrier assembly for locking the supporting member in adjusted position, a locking lever pivotally connected with the said locking means for locking engagement with the said closure, and the said locking means being also effective for locking the lever in an adjusted position.

40. 4. A device for adjusting relatively movable members, the same comprising a bracket secured to one member, an arm adjustably connected at one end to said bracket and adjustable thereon, the opposite end of the arm being connected to the other member, a flexible cable connected to opposite ends of the arm and being of greater length than said arm, and a guide means for the cable disposed adjacent one end of the bracket.

45. 5. A device for adjusting a movable member relative to a fixed member, the said movable member being hinged by one margin to said fixed member, said device comprising an elongated slotted bracket secured to said fixed member, an arm pivotally connected at one end to

said bracket and adjustable lengthwise thereon, in a direction toward and away from the hinged connection of the members, the other end of the said arm being pivotally connected to the movable member, a cable connected at its ends to the ends of the arm, and a guide means engaging an intermediate portion of the cable and located in spaced relation to the bracket engaging end of the arm in a direction toward the hinged connection between the movable and fixed members.

5. 6. A device for adjusting storm windows and screens in a window frame, the same comprising a bracket secured to the frame, an arm adjustably connected at one end to the bracket and adjustable to vary the projection of its outer end from the frame, a pin at the outer end of the arm, connecting units secured to the storm windows and screens, each of said units comprising a socket element recessed into the surface of the window or screen and having an opening in its wall for the pivotal reception of the pin at the outer end of the arm, and a spring secured in the said socket element for engaging the outer end of the arm and normally and releasably retaining the pin in engagement with the socket.

10. 7. A device for adjusting storm windows and screens in a window frame, the same comprising a bracket secured to the frame, an arm adjustably connected at one end to the bracket and adjustable to vary the projection of its outer end from the frame, a pin extended from the outer end of the arm, exteriorly threaded socket elements screwed into the storm windows and screens, the said socket elements having openings in their walls for releasable and pivotal engagement with the pin at the outer end of the arm as the windows and screens are changed and replaced in the window frame, and each of the said socket elements including a spring arranged to engage the outer end of the arm and retain the pin in the said opening.

15. 8. A device for adjusting a movable member with respect to a fixed member, comprising a bracket secured to the fixed member, an arm pivotally connected between the bracket and movable member and adjustable on said bracket, locking means on the bracket for locking the arm in adjusted position, said locking means including a stud and a screw knob thereon, a locking lever fulcrumed on the stud, a curved hook extending from the locking lever, and a connecting means secured to the movable member for locking and camming engagement with the said hook to thereby draw the movable member to closed position with respect to the fixed member.

20. 9. A device for adjusting and locking a movable member with respect to a fixed member, the same comprising an arm adjustably connected at one end to the fixed member and pivotally connected at its other end to the movable member, means for locking the arm in adjusted positions, a lever associated with the said arm locking means and pivotally connected therewith, a hook extended from one end of the lever for releasable engagement with the movable member, and a handle extending from the other end of the lever for oscillating the same about its pivotal connection and engaging and releas-

70. 75. 80. 85. 90. 95. 100. 105. 110. 115. 120. 125. 130. 135. 140. 145. 150. 155. 160. 165. 170. 175. 180. 185. 190. 195. 200. 205. 210. 215. 220. 225. 230. 235. 240. 245. 250. 255. 260. 265. 270.
